A. J. KERCHER

AUTOMOBILE RADIATOR HEATER

Filed June 12, 1922

FIG. 2.

FIG. 2.

WITNESS:
H. S. Hedgpeth

INVENTOR,
ARTHUR J. HERCHER.
BY *white Frost & Evans*
his ATTORNEYS.

UNITED STATES PATENT OFFICE.

ARTHUR J. KERCHER, OF BERKELEY, CALIFORNIA.

AUTOMOBILE RADIATOR HEATER.

Application filed June 12, 1922. Serial No. 567,875.

To all whom it may concern:

Be it known that I, ARTHUR J. KERCHER, a citizen of the United States, and a resident of Berkeley, county of Alameda, State of California, have invented new and useful Automobile Radiator Heaters, of which the following is a specification.

This invention relates to means for heating the usual water cooler or radiator common to many forms of combustion engines, and especially vehicle motors.

An object of the invention is to provide a simple, inexpensive, practicable and effective device for warming up the circulation water in a motor radiator.

An object is to provide an automatic apparatus which can be set to become effective at any predetermined time to warm up the radiator.

Another object is to provide for economy in operation of the device.

Further, an object is to provide a device that can be readily stored or placed in a convenient location when not applied and which can be easily adjusted, in heating position, in front of the radiator and is adapted to be attached to the filling spout of the radiator.

The invention possesses other objects and features of advantage, some of which, with the foregoing, will be made manifest in the following description of the preferred form of the invention, which is illustrated in the drawings accompanying and forming part of the specification. It is to be understood that it is not intended to limit the invention to the embodiment shown by the said drawings and description, as variations may be adopted within the scope of the invention as set forth in the claims.

Fig. 1 is a perspective of the device as applied.

Fig. 2 is a vertical section of the device and the radiator, and shows, in diagram, the automatic controlling means.

Fig. 3 is a more detail view of the controlling means.

My invention consists of a device adapted to be suspended in front of the radiator conduits of a cooling system. Preferably the device includes means for attachment to the usual filling spout and, therefore, requires no alteration of, nor special attach-

ments to, the given radiator to which the device is made applicable. The invention also includes an automatic control means.

The disclosed form of the invention embodies a curtain like element 2 preferably of asbestos or other heat resistant material: the curtain, obviously being variously designed according to different radiators to which it may be attached. At the top of the curtain is a flange or flap 3, perforated at 4 to pass down over the spout 5 of a radiator R. The lower end of the curtain is formed with a transverse pocket or chamber 5 at the bottom so as to be disposed in front of the radiator and near its bottom. The pocket opens toward the radiator in a wide mouth and in the pocket is arranged a suitable heating element, as an electric resistance coil 6 served by electric conductors 7-8. The walls of the pocket 5 flare toward the radiator so as to reflect the heat generated by the hot coil 6.

It may be desired to start to heat up the motor radiator at a predetermined time, as in the morning, without the presence of the driver or other person. To that end I provide automatic means to turn on the electric current for the heater, and also provide means for automatically intermittently breaking and closing the circuit after the heat under the curtain reaches a suitable degree. Such means may comprise a time device, as a clock C, having a switch or circuit closing connection 10 with one of the service conductors 7-8. The clock, being set to "go off" at a desired time, will then close the circuit and the heater energized.

To automatically break the circuit at a certain heat under the curtain this latter is provided with a chamber 11 at its upper portion. In this chamber is arranged a simple thermostatic device 12 which is connected to a lever 13 forming a means for opening and closing the circuit through the wires 7-8. The lever may have a contact piece 14 to engage a co-ordinate contact piece 15 while the temperature is below the given high degree. As this high degree is reached, the device 12 operates to break contact at contact pieces 14-15. When the heat falls the circuit is again automatically closed by means of the thermostat 12. This economizes in current consumption.

It is understood that the apparatus may be installed in a garage or elsewhere, it only being necessary to hang the curtain over the radiator and close the circuit to heat up the radiator at the desired time.

I claim:

1. A device for warming motor radiators comprising an electric heating element, means for suspending the element adjacent the lower part of the radiator and a reflector arranged behind the heating element to reflect radiated heat against the radiator.
2. A device for warming motor radiators comprising an electric heating element, means for suspending the element adjacent the lower part of the radiator, a circuit for the heating element and a thermostat controlling said circuit arranged adjacent the upper portion of the radiator.
3. A device for warming motor radiators comprising an electric heating element, means for suspending the element adjacent the lower part of the radiator, a reflector arranged behind the heating element to reflect radiated heat against the radiator and a thermostat controlling the flow of current

through the heating element and arranged adjacent the upper portion of the radiator.

4. A device for warming motor radiators comprising an electric heating element, means for suspending the element adjacent the lower part of the radiator, a pocket in which the heating element is disposed whereby the heat generated is radiated against the radiator, said pocket opening only against the face of the radiator so that there is no draft of air through the pocket.

5. A device for warming motor radiators comprising an electric heating element, means for suspending the element adjacent the lower part of the radiator, a pocket in said suspending means in which said heating element is disposed so that the radiator is heated by radiated heat, a circuit for the heating element, a second pocket in the suspending means disposed adjacent the upper portion of the radiator and a thermostat in said second pocket controlling the flow of currents through said circuit.

In testimony whereof, I have hereunto set my hand.

ARTHUR J. KERCHER.
